UNITED STATES PATENT OFFICE.

JOHN S. DOREMIRE, OF CHALMERS, INDIANA.

DITCHING MACHINE.

Application filed October 20, 1921. Serial No. 509,105.

To all whom it may concern:

Be it known that JOHN S. DOREMIRE, a citizen of the United States, residing at Chalmers, in the county of White and State 5 of Indiana, has invented certain new and useful Improvements in Ditching Machines, of which the following is a specification.

This invention has relation to certain new and useful improvements in a ditching machine and has for its primary object the provision of a machine of this character which will be constructed in such a manner that the ditch may be readily formed by the cutting blade which serves to throw the dirt 10 from upon the lower end of the elevator, from which it is carried by the transverse conveyor to the side of the ditch, the cutting blade being mounted in such a manner at the forward end of the elevator as to be automatically adjustable to properly cut through 15 the soil and form the ditch.

The invention has for another object the provision of a ditching machine of the character stated which will be of comparatively 20 simple and inexpensive construction, in which the parts will be arranged so as to give the proper pull or strain upon the cutting blade, regardless of the depth of the ditch and the corresponding angle of the incline of the cutting blade, thereby causing 25 the elevator and the conveyor to follow the cutting blade without exerting any unnecessary strain or exertion upon the latter.

The invention has for a further object 30 the provision of a ditching machine of the character stated in which the cutting blade carrying beam will have pivotal connection with the forward end of the elevator frame mounted on the axle carrying the ground 35 wheels near the rear end of the elevator and forwardly of the transverse conveyor mounted beneath the upper end of the elevator conveyor, thereby properly connecting all of the parts of the device so that the machine 40 may be properly guided by the assistance of the adjustably mounted forward guide wheel depending beneath the beam at a point between the cutting blade and the forward end 45 of the beams on which is mounted the up-standing clevis receiving member for the draft element supporting clevis, the connected parts of the machine being properly

braced so as to assure full cooperation of the various operative parts to attain the highest efficiency for the machine.

A still further object of the invention resides in the provision of a ditching machine of the character set forth in which will be mounted novel supporting beams and a novel form of blade mounted thereon as well 55 as a special connection between the said beams and the forward end of the elevator frame, so as to permit of proper swinging movement of these parts with respect to one another for automatic adjustment of the incline of the cutting blade, which latter is preferably wider at its lower portion to provide for a proper cutting of the ditch and prevent binding of the sides of the elevator frame against the inner side walls of the 60 ditch as this frame depends with the ditch, during the operation of the machine.

The invention has for still another object the provision of a novel form of ditching machine of the character set forth in which 65 the elevator and the transverse conveyor may be readily operated from the axle of the machine during operation of the machine over the ditch being formed.

With the foregoing and other objects in view as will appear as the description proceeds, the invention consists in the novel construction, combination and arrangement of cooperating elements as hereinafter more specifically set forth, claimed, and shown in 80 the accompanying drawings forming a part of the present application and in which:—

Figure 1 is a side elevation of the improved form of ditching machine.

Figure 2 is a top plan view of the machine 90 as shown in Fig. 1.

Figure 3 is a longitudinal section through the machine with parts shown in elevation.

Figure 4 is an enlarged detail elevation of the rear portion of the machine, showing the 95 driving means for the elevator and the transverse conveyor.

Figure 5 is a plan view of the parts shown in Fig. 4, with portions of the elevator and conveyor broken away, this view showing 100 the operating means for the parts of the machine.

Figure 6 is a detail elevation of the cutting blade.

Figure 7 is a detail transverse section on the plane of line 7—7 of Fig. 3, looking in the direction indicated by the arrows.

Referring more in detail to the drawings in which similar reference characters designate corresponding parts throughout the several views, 1 indicates the cutting blade which is preferably of the form shown in Fig. 6 of the drawings, decreasing slightly 10 in width towards its upper end and having the pointed lower edge 1', as clearly shown. The advantage of this form of cutting blade will be apparent, as it is evident that such a blade when mounted on the turned and forwardly and downwardly directed end 2 of the rearwardly diverging beam 3, will result in cutting a ditch or channel which will be the same width from top to bottom. The width of the blade 1 at its widest portion 15 is more than equal to the width of any part of the machine which may enter the ditch, thereby preventing all possibility of the machine or any part thereof binding against the inner walls of the ditch or channel during the cutting operation. This may 20 be better understood as the description proceeds.

The main portions of the beam 3 are inclined downwardly and slightly decreasing 30 in size toward their connected forward end, as shown clearly in Fig. 2. The standard 4 extends upwardly from the connected forward ends of the beams 3, as shown in Fig. 1, and is provided with a series of spaced 35 openings 5 within which may be secured the draft supporting clevis 6 for the draft mechanism or draft element 7. This makes it possible to readily adjust the position of the clevis 6 vertically on the standard 4, according 40 to the depth of the ditch or channel and the incline of the cutting blade 1. A suitable bracing member 8 may be connected with the upper end of the standard 4 and with the beams 3, as shown in Fig. 1, to properly 45 brace and support the standard 4. A rearwardly directed resilient seat supporting member 9 is connected at its lower end with the separated rear ends of the beams 3, adjacent the point at which these beams are 50 curved and directed downwardly and forwardly, as previously stated, the member 9 serving to support on its upper end the driver's seat 10 rearwardly of the blade 1, as shown clearly in Fig. 1 of the drawings.

In order to properly guide the machine and also regulate the depth of cut of the blade 1, the forward guide wheel 11 is employed this wheel being mounted on the forward axle 12 carried in the bent or turned portion of the angular supporting member 13 extended between and projecting below the beams 3, as shown in the drawings. One arm of the member 13 is directed forwardly and secured between the beams 3, as shown at 13' while the remaining arm 14 thereof is ex-

tended upwardly between the beams 3 and pivotally connected with the adjusting arm 15. This arm 15 is rigidly mounted on a shaft 16 having bearings 16' provided therefor on the upper edge of the beams 3, near the rear end thereof and a short distance forwardly of the driver's seat 10. A lever 17 is also rigidly connected with the shaft 16 to operate the latter. This lever 17 may be locked in adjusted position by engaging the locking finger 18 thereof with the rack segment 19, which latter is also rigidly mounted on the beams 3. The lever 17 has a releasing finger 20 connected in a suitable manner with the locking finger 18 so as to withdraw the latter from the rack segment 19 when it is desired to operate the lever 17 for adjustment of the wheel 11 with respect to the beams 3.

The downwardly and forwardly rear turned ends 2 of the beams 3 have rearwardly directed perforated ears 21, through which the shaft 22 is extended. The shaft 22 also projects through the lower forward ends of the elevator frame members 23, positioned between the ends 2 of the beams 3, thereby forming a pivotal connection between the beams 3 and the elevator structure. This shaft 22 also serves as the lower shaft of the elevator and carries a roller 24 which serves, together with the upper roller 24' of the elevator, mounted on the upper elevator shaft 26, to support the elevator belt 27 having the usual transverse members or steps 28, so that the elevator may serve to carry upwardly and discharge from its upper end the dirt deposited thereon by the blade 1, the lower end of the elevator belt 27 traveling beneath the upper edge portion of the cutting blade 1, as shown in Fig. 3. Suitable brace bars 29 are provided for bracing the elevator structure and the beams 3, these brace bars 29 being positioned on opposite sides of the machine and having their forward ends pivotally connected with the curved portions of the beams 3 while their rear ends are loosely connected with the side frame members 23 of the elevator structure, as shown clearly in the drawings. Mounted in suitable bearings 30 beneath the upper rear end portions of the elevator structure, is the rear axle 31 which extends transversely of the elevator, as clearly shown in the drawings and has mounted on its extended end portion the ground wheels 32. This rear axle 31 preferably has the wheels 32 rigidly mounted thereon and carries a drive gear 33, meshing with the gear wheel 34 on the stub-shaft 35 also carried at the lower portion of the elevator frame structure, as shown in Figs. 125 and 4. It will therefore be seen that as the machine travels forwardly, the stub-shaft 35 will be given a rotation in the reverse direction. This shaft 35 has a sprocket wheel 36 mounted thereon with the sprocket chain 37

engaged therearound. This sprocket chain 37 also engages the sprocket wheel 38 on the upper shaft 26 of the elevator. The upper shaft 26 of the elevator has an extended end 5 with a belt pulley 39 mounted thereon to accommodate the drive belt 40 extended therearound and around the corresponding belt pulley 41 carried by the shaft 42 of the transverse conveyor employed for conveying the dirt to the side of the ditch and discharging the same. This conveyor 42 carries one end roller 43 of the transverse conveyor belt and around which rollers the conveyor belt 44 is engaged. The belt 44 has the usual 10 transverse members or steps 45 mounted thereon, as shown in the drawings. Both of the rollers 43 on the end shafts 42 are given the same numbers and the shafts 42 extend through the longitudinal frame members 46 of the transverse conveyor structure. The conveyor structure is suspended from the upper rear end of the elevator by suitable suspending bracket members 47, as shown in the drawings. It is also to be noted 15 from Fig. 1 of the drawings that the transverse discharge conveyor structure is of such length as to extend for a short distance to one side of the machine and pass the ground wheel 32 for this side of the machine. It will be evident from the description of the 20 operating means for the conveyor and the elevator of this machine that both of the parts will be operated automatically in the proper direction as the machine moves over the surface for digging the ditch or channel, without the necessity of providing any other auxiliary operating mechanism.

It is believed the complete construction and operation of this machine may now be 25 apparent from the foregoing paragraphs taken in connection with the accompanying drawings without further detailed description. The operation may be briefly stated, as follows. After proper adjustment of the clevis 6 on the standard 4 and the wheel 11 by proper placing of the adjusting lever 17, the machine may be drawn over the ground and the cutting blade 1 will enter the ground 30 properly, extending the desired distance into the same and riding on the proper angle or incline to cut the channel or ditch desired, the width of the lower or cutting end of the blade being of increased width so as to provide a ditch or channel of sufficient width to 35 prevent the sides of the elevator frame and the beams 3 from binding upon the side walls of the ditch or channel as they depend into the latter as the machine moves over the surface, rotation of the ground wheel 32 and the rear axle 31 will cause proper operation 40 of the elevator belt 27 and the conveyor belt 44, as previously stated so as to carry upwardly the dirt deposited on the elevator by the cutting blade 1 and then carry the dirt to 45 the side of the ditch and discharge the dirt

at a desired distance from the side of the ditch, as previously stated. It is believed that further description is unnecessary.

While the preferred embodiment of the invention has been shown and described, 70 it is to be understood that minor changes in the details of construction and arrangement of parts may be resorted to within the scope of what is claimed without departing from the spirit of the invention. 75

What is claimed is:

1. A ditching machine comprising supporting beams having turned and separated end portions, a cutting blade mounted on said end portions, draft element supporting beams mounted on the opposite end portions of said beams, a depth regulating and guiding member mounted adjustably in said beams, means for controlling the last mentioned member, a driver's seat mounted on said beams and rearwardly of said cutting member, an elevator structure pivoted at its lower end to said turned and separated ends of the beams opposite said cutting member, and a transverse discharge conveyor suspended beneath the upper end of said conveyor to receive material therefrom. 80

2. A ditching machine rearwardly diverging beams connected at their forward ends, a standard mounted on the forward ends of said beams, bracing means for said standard, said standard being adapted to have a draft element adjustably mounted thereon, a depth regulating and guide wheel, means 90 for adjustably mounting said wheel beneath said beams, means for regulating the position of said wheel, said beams having turned rear ends directed forwardly and downwardly, a cutting blade mounted on 95 said last mentioned ends of the beams, the cutting blade having a pointed lower edge and decreasing gradually in width towards its upper end, the wider portion of the cutting blade extending past the sides of 100 said beams, an elevator structure having its, lower end portion pivoted between the turned lower ends of said beams, bracing connections between said beams and said elevator structure, and a discharge conveyor 105 extended to one side of the machine and having an end portion suspended beneath the upper end of said conveyor structure. 110

3. A ditching machine comprising supporting beams, an elevator structure pivotally connected at its lower forward end to the supporting beams, means carried by said beams to receive a draft element, means for tilting said beams and varying the respective inclinations of said beams and said elevator structure, a cutting element depending from said beams, the incline of said cutting element being varied with the tilting of said beams, the rear supporting 120 axle for the machine mounted transversely 125

beneath the upper portion of said elevator structure, driving connections between said rear axle and the elevator proper of said elevator structure, ground wheels rigid with said rear axle, a side delivery conveyor structure suspended from the upper portion of the elevator structure, and driving

connections between the elevator proper and the conveyor proper of said conveyor structure.

10

In testimony whereof I affix my signature.

JOHN S. DOREMIRE.
